REVERSIBLE AND STACKABLE GAME PIECE

Henry A. Wilson, 1000 Eldorado Ave.,
Clearwater Beach, Fla.

Filed Dec. 6, 1963, Ser. No. 77,705

Term of patent 14 years

(Cl. D34—5)

Fig. 1

Fig. 3

FIG. 1 is a perspective view of a reversible and stackable game piece showing one of identical reversible faces embodying my new design;

FIG. 2 is a plan view thereof;

FIG. 3 is a side elevational view of the game piece of FIG. 1.

I claim:

The ornamental design for a reversible and stackable game piece, substantially as shown and described.
